UNITED STATES PATENT OFFICE

2,359,567

OIL BURNER UNIT

Samuel J. Levine, Verona, N. J., assignor to General Electric Company, a corporation of New York

Application May 21, 1942, Serial No. 443,900

8 Claims. (Cl. 158—76)

This invention relates to oil burners, and the principal object is to provide an improved form of automatic, electrically operated oil burner unit suitable for application to various types of furnaces and boilers for operation under thermostatic control in domestic heating service.

The invention provides improvements upon the oil burner unit disclosed and claimed in the Macchi Patent No. 2,311,404 of February 16, 1943, and assigned to the assignee of the present invention.

A special object is to provide an improved form of combustion air blower superstructure having both the air inlet and air outlet formed in the under side thereof so as to serve in conjunction with an air inlet skirt suspended therefrom adjacent to the floor as a noise suppressing enclosing jacket for the other parts of the unit.

A further object is to provide a more quiet oil burner unit by having a vertical electric motor driven air compressor and oil pump mechanism resiliently seated in an adjustable height, floor mounted base to counterbalance a burner head projecting horizontally therefrom and by having a specially formed overhanging centrifugal blower scroll casing carried at the top of the mechanism with an air inlet skirt removably suspended therefrom adjacent to the floor for suppressing the noise of the mechanism while providing ready access to the various operating parts and connections of the unit.

Another object is to provide the under side of the blower casing within the skirt with both an annular air inlet mounting drum having flow equalizing ports and a cooperating adjustable band for restricting the air flow and an offset air outlet orifice flexibly connected with a special combined air and high voltage ignition transformer connection box formed at the inlet end of the burner nozzle so as to constitute a non-rectilinear series of sonic filter pulsation chambers of differing size and shape along the path of the air flow for further dampening and suppressing both high pitched blower and low pitched combustion noise.

A still further object is to decrease the temperature rise of the burner head on shut-down by minimizing the heat storage capacity of the parts and at the same time reducing the unbalancing effect of the horizontally projecting burner head overhanging the supporting base, thereby enabling a specially formed lightweight base and burner head supporting structure to be employed.

A preferred embodiment of the invention is illustrated in the accompanying drawing in

which Fig. 1 is a vertical sectional view of the improved form of conversion oil burner unit; Fig. 2 is a top view of the unit with parts of the overhanging blower casing broken away in order more clearly to reveal the details of construction of the burner head air inlet and supporting box and the other parts of the unit located beneath the casing; Fig. 3 is a partial sectional view along the line 3—3 of Fig. 2 showing the vertical electric motor driven oil pump and air compressor mechanism provided with the special inverted bell mounting for the blower and the concentric mounting for the annular air inlet drum around the bell; and Fig. 4 is a sectional view along the line 4—4 of Fig. 1 showing more clearly the construction of the various parts of the unit, particularly the scroll forming dividing wall and cut-off within the blower casing and also the removable access door with which the interconnected burner head air inlet and supporting box is provided.

Referring to Figs. 1 and 3, the vertical axis electric motor driven oil and air pressure supply mechanism 10 of the unit has a combined oil pump and air compressor 11 mounted inside of the oil and air pressure sump 12 with the vertical shaft 13 carrying the rotary pump blade 14 and also the outer overhanging rotor 15 of the induction type electric motor 16 having the outwardly open stator field structure 17. The oil pump and air compressor mechanism 10 serves to supply both oil and air under pressure to the horizontal oil and air discharge tubular burner head indicated generally by the reference character 18 and as shown is of the improved type described and claimed in the Lum Patent 2,032,291, granted February 25, 1936, although any other suitable type of oil pumping means may be employed if desired. Hence, the detailed structure thereof need not be further described.

For resiliently mounting the motor driven pumping mechanism 10, the clamping ring 20 that holds the pressure sump 12 sealed to the end bearing plate 21 is provided with suitable recessed mounting lugs 22 for receiving the helical mounting springs 23 that resiliently engage with suitable positioning bosses formed on the supporting base plate 24. Base plate 24 is provided with an enlarged central opening 25 for permitting the sump 12 to hang therethrough at a low level relative to the horizontally projecting tubular burner head 18 so as to lower the center of gravity of the operating mechanism and thereby help stabilize the unit upon the adjustable legs 26 for varying the height of the

base plate 24 above the floor and for levelling the unit.

The centrifugal combustion air blower wheel 30 is provided with a special air flow guiding reentrant mounting element 31 in the form of an inverted bell, as shown in Fig. 3, so that it may be mounted on the upper end of the motor driven shaft 13 by means of the holding-down nut 32. The split scroll casing 33 for blower 30 is formed of the lower plate 34 and the upper plate 35, each having a semicircular rounded end opposite a square end. The lower plate 34 is carried by the annular air inlet drum 36 which is secured in coaxial alignment with the blower wheel mounting bell 31, as shown in Fig. 3, to the motor 16 by means of the resilient mounting washer 37 and the clamping screw 38 so that the hum vibrations produced by the motor stator field 17 are not readily amplified by the blower casing structure. The annular air inlet drum 36 is provided with a plurality of flow equalizing ports 39 with which the correspondingly apertured adjustable band 40 cooperates to vary the effective area of the inlet ports to the blower and thereby regulate the air flow. The lower plate 34 of the blower casing is provided with an upturned circular air inlet orifice 43 concentric with the annular air inlet drum 36 and the wheel mounting bell 31 but slightly eccentric with the semicircular end of the scroll casing 33 and through which the mounting bell 31 of the blower wheel 30 projects to form therewith an annular restricted opening from the air inlet drum 36 into the blower casing 33. The lower plate 34 also is provided with a rectangular air outlet opening 44 offset from the air inlet opening 43 into one corner of the rectangular end of plate 34 and having downturned edges 44a for connection with the upwardly open air inlet box 45 of the air discharge nozzle tube 46 of the burner head 18 by means of the flexible joint 47, preferably formed of canvas or other suitable material clamped to the upper edges of the box 45 and the downturned edges 44a of the opening 44.

The top plate 35 of the blower casing as shown is pressed into a dome form with a depending rim so that the circular and rectangular edges thereof will match and engage with the corresponding edges of the lower plate 34. Top plate 35 preferably is also provided with a suitably formed central strengthening rib 48 to prevent resonant deformation of the enlarged arched dome. Thus, as shown in Figs. 1 and 2, the two plates 34 and 35 constitute a flat blower casing of symmetrical form having a rounded end with the air inlet orifice 43 located centrally in the under side thereof, and having a square end with the air outlet opening 44 offset into a corner thereof.

In order to provide a scroll passage 48 around the blower 30, as well as a dead air noise suppressing chamber 49 in the blower casing, a specially formed dividing wall 50 is interposed between the plates 34 and 35. Preferably, the dividing wall 50 is provided with suitable lugs 51, as shown in Fig. 4, that interlock with corresponding slots formed in the bottom plate 34 to anchor the dividing wall 50 in its proper position. A specially rounded double wall cut-off vane 52 extends from the dividing wall 50 into proximity to the periphery of the blower 30 with both walls of the cut-off vane in slightly spaced apart relation with each of the blower casing 75

plates 34 and 35, thereby tending to prevent or suppress high pitched air noise vibrations at the blower cut-off.

The removable enclosing and air inlet skirt 60 for the unit is suspended from the blower casing, being secured to the edges thereof by the holding screws 61 so as to form a large air inlet chamber for the blower surrounding the air inlet drum 36. The skirt 60 is formed into an arched or U shape with the edges turned at both the bottom and top to fit the blower casing snugly with only an open gap at the square end so that the skirt may be readily removed from the unit upon loosening the screws 61. This open arched or U shape with the turned channel edges stiffens the enclosing skirt 60 sufficiently to prevent vibration and insure that it remain properly suspended in position on the blower housing even though entirely unsupported at the bottom.

The combined air inlet and high voltage ignition connection box 45 is formed by a special vertical channel brace member 65 having outward edges 66 at the bottom thereof firmly joined to the base 24, preferably by welding, and the outward edges 67 at the sides thereof similarly joined to the upturned end wall 68 of the base 24. Thus this special channel brace member 65 serves not only to form the open top air inlet box 45 but also to brace and stiffen the upturned wall 68 which is provided with the pressed out circular rim 70 projecting from the air box for mounting the outer air nozzle tube 46 of the burner head 18. This air nozzle tube 46 preferably is formed of lightweight steel so that it may be readily welded into the rim 70 and carries the renewable cast iron nozzle tip 72 at the end thereof projecting into the furnace.

The channel brace member 65 that cooperates with the base 24 and the upturned end wall 68 thereof to form the combined air and connection box 45 is provided with a specially formed access door 75 having a central opening 75a and means for removably sealing therein the air pressure tube 76 and the oil pressure tube 77 which interconnect the inner oil atomizing nozzle 78 of the tubular burner head 18 with the electric motor driven oil and air pressure supply mechanism 10. This is accomplished by mounting the tubes 76 and 77 in sealed engagement with the enlarged central part 80 of the supporting strut 81 so as to slope away from nozzle 78 slightly. Strut 81 has its ends bent over to be received into specially depressed slots 82 formed in the channel brace member 65 adjacent the top and bottom edges of the access opening 83 that is covered by the access door 75. As shown more clearly in Fig. 4, the left-hand edges of the access opening 83 are pressed out into a semi-circular channel shape for receiving the semi-circular end of the access door 75 which is held in its closed position in sealing engagement with part 80 and the edges of opening 83 by the screws 84.

The special channel shaped brace member 65 is provided with suitable mounting slots for receiving the end lugs of the curved air directing blade 85 that extends across the air box 45. This box 45 also is provided with a suitable opening 86 for receiving the high voltage terminal insulator block 87 of the ignition transformer 88 from which the conductors 89 extend through the spacer 90 to the insulated terminals 91 for the arcing electrodes 92 that are located adjacent

the end of the inner oil atomizing nozzle 78 of the burner head 18. The ignition transformer 88 is held in sealing engagement with edges of opening 86 by the bolts 93. The inner oil atomizing nozzle 78 is shown as provided with a series of air directing vanes 95 that slidably engage with the inside of the outer air tube 46 of the tubular burner head 18 for supporting the inner nozzle 78 and the arcing electrodes 92 in proper position therin when the strut 81 is sealed in position by the access door 75.

In operation the ignition transformer 88 and the electric driving motor 16 of the air and oil supply mechanism 10 are suitably energized in proper sequence by means of any usual automatic oil burner control (not shown) so as to provide an ignition arc adjacent the end of the oil atomizing nozzle 78 and also create a supply of oil and air under pressure in the sump tank 12. The admission of oil under pressure from the sump tank 12 to the atomizing nozzle 78 preferably is controlled by an electromagnetic valve 97 shown diagrammatically in the drawing. The flow of combustion air from the blower 30 is regulated by loosening the clamping screw 41 and sliding the band 40 to vary the effective area of the equalizing ports 39 formed in the annular air inlet drum 36 thereby decreasing or increasing the amount of combustion air supplied to the nozzle tube 46. Due to the non-linear series of sonic filter pulsation chambers of different sizes and shapes formed along the path of the air flow, both the high pitched oscillations produced by the blower and the low pitched oscillations or rumble produced by combustion at the burner nozzle are effectively damped and suppressed.

Thus the improved unit is exceptionally quiet since the air must flow from adjacent the floor outwardly around the base 24 and into a relatively large annular sonic filter pulsation chamber defined by the base 24 and its upturned right-hand end 68, the arch channel enclosing skirt 60 and the lower plate 34 of the blower housing with the motor driven mechanism located centrally therein. The air flow then divides and passes inwardly through the flow equalizing openings 39 into a relatively small restricted annular chamber defined by the drum 36 and the mounting bell 31 of the blower as well as by the cooperating blower inlet orifice 43 and the outwardly open stator 17 and rotor 15 as shown in Fig. 3. Thus an effective noise suppressing action as well as increased cooling of the motor stator and rotor results from the rapid annular blower inlet air flow provided by orifice 43, drum 36 and bell 31 during operation of the unit. Then, after passing through the blades of the centrifugal fan 30, the air flows around through the scroll shaped chamber formed by the fan housings 34 and 35 in conjunction with the dividing wall 50 and the cut-off 52 and is then diverted through the flexible joint 47 into the rectangular air box 45 wherein the air flow is again diverted and finally passes through the cylindrical air tube 46 and the nozzle 72 into the furnace. The dead air noise suppressing chamber 49 formed behind the dividing wall 50 helps somewhat to dampen and suppress any high pitched air vibrations created at the cut-off 52 of the centrifugal fan. The relatively long circuitous air path from the bottom of the skirt 60 to the air nozzle 72 serves to dampen and suppress the low pitched vibrations or rumbles produced by combustion at the end of the burner head 18.

The resilient mounting of the vertical motor 75

driven mechanism 10 intermediate its ends with the added weight of the blower housing and enclosing skirt tends to lessen the mechanical vibration of the mechanism. Also, the flexible air connection 47 tends to dampen mechanical vibration. The light weight of the burner head parts materially reduces the heat storage mass thereof so that when the operation of the burner is stopped, there is relatively little heat stored therein to cause overheating of the oil nozzle 78. The isolation of the high voltage terminals of the ignition transformer 88 and the leads 89 therefrom within the air box 45 and the air tube 46 effectively prevents any accidental contact therewith and thereby makes the unit more safe for installation in the home. Still the access door 75 may be readily removed by the service man to permit the oil atomizing nozzle 78 and its associated parts readily to be withdrawn from the air tube 46 for inspection or repair through the opening 83 after the ignition leads 89 are disconnected from the transformer terminals.

What I claim as new and desire to secure by Letters Patent of the United States, is:

23. In an oil burner, a vertical axis blower casing having a round end opposite a square end, and provided with an interior dividing wall forming a blower scroll having an air inlet orifice and an air outlet opening formed in the under side of said casing with said orifice disposed eccentrically in said round end and said outlet opening offset into a corner of said square end, a U-shaped air inlet skirt suspended from the periphery of said blower casing and having a gap at the square end thereof, an upwardly open air box having a flexible joint for communicating with said outlet opening and having a lateral wall extension for substantially closing said gap and provided with a floor mounted base having the perimeter thereof in spaced apart relation with said skirt adjacent the bottom edge thereof, an air discharge nozzle tube projecting from said air box through said gap, and a vertical axis electric motor driven oil and atomizing air pumping mechanism resiliently seated in said base and provided with mounting means for carrying said blower casing over the top thereof and having an oil discharge nozzle mounted in said air nozzle tube and a combustion air blower wheel rotatable at the top thereof in said blower scroll.
2. In an oil burner, a vertical axis blower casing having an air inlet orifice formed in the under side of said casing and a dividing wall forming a scroll about said orifice, an inlet drum surrounding said orifice and having a plurality of flow equalizing ports and adjustable means for varying the effective area of said ports to regulate the air flow, an air inlet skirt suspended from said casing around said drum and having a gap at one side thereof, an air outlet box communicating with the under side of said casing and having a wall extended for substantially closing said gap and provided with a floor mounted base disposed within said skirt, an air discharge nozzle tube projecting from said box, and a vertical axis electric motor driven oil and atomizing air pumping mechanism carried within said skirt by said base and provided with mounting means for engaging with said inlet drum to carry said blower casing over the top of said mechanism and having an oil discharge nozzle mounted in said air nozzle tube and a combustion air blower wheel provided with a re-entrant mounting bell projecting through said drum and inlet orifice for rotation of said wheel in said blower casing.

3. In an oil burner, a vertical axis blower casing having an air inlet orifice formed in the under side of said casing and a dividing wall forming a scroll about said orifice, an air inlet skirt suspended from said casing and having a gap at one side thereof, an air outlet box communicating with the under side of said casing and having a wall extended for substantially closing said gap and provided with a floor mounted base disposed within said skirt, an air discharge nozzle tube mounted in and projecting from said box, and a vertical axis electric motor driven oil and atomizing air pumping mechanism carried by said base and provided with mounting means for carrying said blower casing over the top thereof and having an oil discharge nozzle mounted in said air nozzle tube and a combustion air blower wheel rotatable at the top of said mechanism in said casing.

4. In an oil burner, a vertical axis blower casing having an air inlet orifice formed in the under side of said casing, an air inlet skirt suspended from said casing and having a gap at one side thereof, means for substantially closing said gap including an air outlet box communicating with the under side of said casing and provided with a floor mounted base disposed within said skirt, an air discharge nozzle tube projecting from said box, and a vertical axis electric motor driven oil and atomizing air pumping mechanism carried by said base and provided with mounting means for carrying said blower casing over the top thereof and having an oil discharge nozzle mounted in said air nozzle tube and a combustion air blower wheel rotatable at the top of said mechanism in said casing.

5. In an oil burner, a vertical axis electric motor driven oil and atomizing air supply mechanism having a centrifugal blower at the top thereof, a blower casing carried by and overhanging said mechanism and having both an air inlet orifice concentric with said blower and an offset air outlet opening formed in the under side of said casing, a horizontal oil and air discharge burner head having an oil supply connection with said mechanism and having an upwardly open air inlet box disposed beneath said outlet opening and communicating therewith, a base plate extending laterally from said air box for supporting said mechanism and said head, and an air inlet skirt suspended from said casing in spaced apart relation with the perimeter of said base to form an

air inlet chamber for said blower casing surrounding said mechanism.

6. In an oil burner, a vertical axis electric motor driven oil and atomizing air supply mechanism having an overhanging blower casing mounted at the top thereof, a horizontal oil and air discharge burner head having an oil supply connection with said mechanism and having an upwardly open air inlet box at one end thereof disposed beneath said casing and communicating therewith, a floor mounted base extending laterally from said air box for supporting said mechanism and said head, and an air inlet skirt suspended from said casing to form an air inlet chamber for said casing surrounding said mechanism.

7. In an oil burner, a floor mounted horizontal base having an upright wall, a vertical channel brace member secured to said base and wall to form an open top air box, an air discharge nozzle tube mounted in said wall in communication with said air box, an oil nozzle mounted inside said tube, and a vertical axis electric motor driven oil and atomizing air supply mechanism carried on said base and having a vertical axis blower casing mounted over the top of said mechanism and overhanging said air box and provided with an outlet communicating therewith and an oil supply conduit removably mounted in a wall of said air box and communicating with said oil nozzle.

8. An oil burner unit having, in combination, a floor mounted vertical axis electric motor driven oil burner mechanism having a downwardly open blower wheel at the top thereof, a burner head connected with and horizontally projecting from said mechanism and provided with an upwardly open air inlet box beside said mechanism, a closed top blower casing for said wheel overhanging said mechanism, said casing having a round end opposite a square end and having an air inlet orifice and an air outlet opening formed in the under side thereof with said orifice disposed below said wheel in said round end and said outlet opening offset into a corner of said square end above said air box to communicate therewith, and an air inlet skirt suspended from the periphery of said casing adjacent to the floor to form jointly with said casing and air box an air inlet chamber communicating with said blower air inlet orifice and substantially surrounding said mechanism.

SAMUEL J. LEVINE.
